US00D894762S

(12) United States Design Patent (10) Patent No.: US D894,762 S
de Gouzillon de Belizal (45) Date of Patent:  Sep. 1, 2020

(54) HAIR CLIPPER

(71) Applicant: BABYLISS FACO SPRL, Wandre (BE)

(72) Inventor: Charles de Gouzillon de Belizal, Louveigne (BE)

(73) Assignee: BABYLISS FACO SPRL, Wandre (BE)

() Term: 15 Years

(21) Appl. No.: 35/507,165

(22) Filed: Nov. 15, 2018

(80) Hague Agreement Data

Int. Filing Date: Nov. 15, 2018

Int. Reg. No.: DM/202065

Int. Reg. Date: Nov. 15, 2018

Int. Reg. Pub. Date: Aug. 2, 2019

(30) Foreign Application Priority Data

May 18, 2018 (EM) 005272408-0010

(51) LOC (12) Cl. 28-03

(52) U.S. Cl.

USPC D10/53

(58) Field of Classification Search

USPC D28/52, 53, 54

CPC B26B 19/00-08; B26B 19/38-3886

See application file for complete search history.
